UNITED STATES PATENT OFFICE.

ABRAHAM MILLER, OF NEWARK, ASSIGNOR TO NEWARK MACHINE COMPANY, OF COLUMBUS, OHIO.

STRAW-STACKER.

SPECIFICATION forming part of Letters Patent No. 311,137, dated January 20, 1885.

Application filed August 13, 1884. (No model.)

To all whom it may concern:

Be it known that I, ABRAHAM MILLER, a citizen of the United States, residing at Newark, in the county of Licking and State of Ohio, 5 have invented certain new and useful Improvements in Straw-Stackers, of which the following is a specification, reference being had therein to the accompanying drawings.

My invention relates to hinged folding stackers in their relation to ordinary thrashing-machines; and the novelty consists in the construction, arrangement, and adaptation of parts, as will be more fully hereinafter set forth, and specifically pointed out in the claims.

15 The object of the invention is to provide a hinged stacker which, in its relation to a thrasher or separator, may be folded upon and secured to the said separator readily and easily by a single person; that may be readily raised 20 or lowered and easily secured at any desired point of elevation; that folds upon the separator closely and compactly and in such position that when unfolded it falls into the required position for use.

25 The invention is fully illustrated in the accompanying drawings, which form a part of this specification, and in which—

Figure 1 is an elevation showing a hinged stacker unfolded and ready for use, in connection with a separator or huller. Fig. 2 is a similar view with the stacker folded upon the separator. Fig. 3 is a perspective detail of the rear portion of a separator, with a portion of my improvements attached. Fig. 4 is 35 an enlarged detail view of the peculiar hinge which connects the sections of the stacker, and showing also the relation of the adjusting-rods therewith. Fig. 5 is a perspective detail of one of said rods, and Fig. 6 a similar view of one 40 of the web-securing hooks. Fig. 7 is a detail perspective view with the sections of the stacker detached, and two of the slats of the endless belt thereof caught by the securing-hooks, and Fig. 8 is a detail view of the hinge 45 and adjusting-rod secured together.

Referring to the drawings, A designates the body of the separator; B, the body of the straw-elevator frame and endless rake hinged thereto, and C the free section of the stacker hinged 50 to the body B. The sections of the stacker

have the ordinary connections for operating an open-slat belt, D, having transverse slats d, and is of such light construction and material as to be readily manipulated.

To the section C of the stacker is secured 55 one plate, F, of the hinge, which, as an entirety, I will designate by the letter H, while to the body B is secured the fellow plate, F'. Each of these plates has an upwardly-extending arm, upon which is carried the hinge-pivot, 60 so as to bring said pivot out of the line of the sections B C of the stacker, and allow the parts B and C to separate when they are folded, as seen in Fig. 2.

To the part F is secured a cylindrical boss, 65 f, which is received into the sheath f' of the part F'. The sleeve f is hollow, and is of a length slightly greater than the combined width of the eye f' and the eye j of the slotted rod J. A bolt, G, passes through the 70 sleeve f, its head g bearing against the outer face of the plate, and its threaded shank extending inwardly beyond the said boss. A suitable washer, g', passes over the threaded end of the bolt, and a nut, g'', engaged with 75 the bolt, holds the said washer against the end of the sleeve, and this washer holds the slotted rod J and the eye f' between it and the inner face of the plate F securely, but allowing free action of both parts on the boss. By 80 its slot j' the rod J embraces a threaded bolt, K, secured upon the side of the separator, and a wing or tail nut, k, serves to pinch the rod J between it and a roughened metal plate upon the separator, to hold said rod at any desired 85 point of adjustment. This means of adjusting and securing the stacker at any desired angle is simple, efficient, and important. The distance between the supporting-pivot of the elevator-frame B upon separator A and the 90 pivot-bolt G is greater than the distance between the same pivot and the bolts K; hence the rods J always stand on an incline until the body B reaches its highest point of elevation, when they assume a horizontal position, 95 or nearly so, and lie close to the body of the separator. The slots j' are closed slots, and when the nuts k are loosened the upper closed ends of the rods J engage the said bolts K and hold the stacker, as shown in Fig. 1.

Near the upper rear end of each side of the separator is properly journaled a pulley, M, and these pulleys serve an important function in this invention.

5 When it is desired to fold the stacker out of use upon the separator, for transportation or for other purpose, the operator has only to fold the section C upward and over until it rests upon these pulleys M, which are so arranged as to lie squarely in the path of this section when thus folded. As thus partially folded (the nuts k being loosened) the section C rests against the pulleys M with its greater length beyond the points of contact. As thus 15 conditioned the operator has only to lift upon the section C, when the pulleys will allow the free passage of the section C, the weight of the said preponderating portion assisting in the operation until the section C assumes a 20 horizontal position, as seen in Fig. 2, and rests upon the brackets L, secured upon the sides of the separator. By tightening the nuts k all the parts are secured in this position.

When it is desired to again throw the stacker 25 into use, the nuts k need only be loosened and the free end of the section C elevated, when the said section will ride easily over the pulleys M, and the whole be lowered until the bolts K engage the closed upper portions of 30 the slots j in the rods J, when the section C is in position to be readily opened until it assumes a position on the same plane with the body B.

When in a folded position, the web or apron 35 D is liable to "bag" upon the inner or folded side and to get in the way. I provide for this contingency and for holding it securely in place as follows: Upon the upper edge of the body A of the machine-casing I secure hooks 40 P, and upon the lower side of the same body I secure hooks P', as shown.

When the device is folded, the operator has only to unbuckle or unjoint the belt or web D, and engage the end cross-slat, d, with the hooks 45 P upon the upper side, and the last slat d upon the other end with the hooks P'. This engagement holds the web in opposite directions against any displacement. This operation may be done without disjointing the web in some 50 constructions. The tubular sleeve f passes through the eyes f' j', after which the bolt G is passed through the tubular boss and supplied with washer g' and nut g'.

What I claim as new is—

1. In combination with a separator-frame 55 and a folding elevator-frame constructed in sections, slotted rods J, secured to the elevator-frame at one end, and means for securing the other end to the separator-frame, as set forth.

2. In combination with a separator-frame 60 and a folding elevator-frame constructed in sections, slotted rods J, secured to the hinge of the free section of the elevator-frame at one end, and means for securing the other end to the separator-frame, as set forth.

3. In combination with the sections of a hinged stacker and a hinge, H, adjusting rods J, secured to the pivot of the hinge at one end, and means for locking the stacker at any point of elevation, as set forth.

4. In a stacker, substantially as described, the combination of the plate F, having sleeve f, the plate F', having eye f', the bolt G, washer g', and nut g', with the rods J, and locking means, as k, as set forth.

5. In combination with a separator-frame and a hinged elevator-frame, as described, the slotted rod J j, hinge H, and nut k, as and for the purposes set forth.

6. The rods J, having closed slots j, combined with the bolts K, nuts k, hinge H, the elevator-frame, and sections B C, as and for the purposes set forth.

7. In combination with a separator-frame, a hinged elevator-frame, and its slatted apron, 85 as described, hooks secured upon the separator, and adapted to engage the slats d of the apron, and to hold said apron against movement in both directions, as specified.

8. In a stacker, as described, the combination of the sections B C, hinge H, rods J, and nut k, with the separator-frame having bolt K, pulleys M, and brackets L, as and for the purposes set forth.

9. In combination with the separator-frame, 95 the hinged elevator-frame, and apron D, having slats d, the hooks P, secured upon the upper portion of the separator-frame, and the hooks P', secured upon the lower portion thereof, and means for supporting and locking the 100 elevator-frame when folded, as set forth.

In testimony whereof I affix my signature in presence of two witnesses.

ABRAHAM MILLER.
